COMPARTMENTED CAR

Samuel Port, Altoona, Pa.

Application December 11, 1953, Serial No. 397,670

2 Claims. (Cl. 105—376)

This invention relates to a compartmented car and more specifically provides a construction of a mobile transportation vehicle wherein the body may be compartmented for use in transporting articles that require a differential temperature from that of the atmosphere.

An object of this invention is to provide a compartmented car having a plurality of compartments separated by movable sliding partitions wherein the compartments may be joined or separated as desired.

A further object of this invention is to provide a compartmented car having a hollow body portion divided into a plurality of compartments with an access door for each compartment on each side of the body.

A further object of this invention is to provide a compartmented car having a small stationary compartment for heat changing equipment at one end and having a plurality of vertically slideable partitions for separating the remainder of the car into a plurality of compartments.

Yet another object of this invention is to provide a compartmented car having sliding partitions which are capable of being locked into position and which includes ventilating means for circulation of air.

Yet another important object of this invention is to provide a compartmented car which is well insulated, easily compartmented, provided with a plurality of access doors for easier loading and well adapted for the purposes for which the same is intended.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side elevational view of the compartmented car of this invention employed in a railroad car;

Figure 2 is a top plan section taken substantially along section line 2—2 of Figure 1 showing the arrangement of the compartment-forming partitions;

Figure 3 is a longitudinal, vertical section taken substantially along the longitudinal center line of the construction of Figure 1 showing the details of arrangement of the sliding partitions and the guides therefor;

Figure 4 is a transverse, vertical section taken substantially along section line 4—4 of Figure 3 showing the details of construction of one of the sliding partitions; and

Figure 5 is a detailed perspective view showing the construction of the lower end of the sliding partition.

Referring now specifically to the drawings, it will be seen that the numeral 10 generally designates a compartmented railroad car having the usual walkway 12 on the top and ladder 14 on the side. The railroad car 10 is provided with longitudinal support beams 16 and the usual wheel carriage 18 whereby the railroad car may be moved along the rails in the usual manner. The railroad car 10 further includes a bottom 20, vertical side

2

walls 22 and a top 24 all of which are insulated as indicated by the numeral 26 in the usual manner.

As shown in Figure 2, end walls 28 are provided which are substantially the same as the side walls 22 and extending transversely between the side walls 22 is a permanent partition 30 which is in spaced relation to one of the end walls 28. Heat exchange equipment 32 may be positioned in the small compartment formed by the stationary partition 30 and one of the side walls 22 may be provided with a door 34 for inspecting, repair and maintenance of the heat exchange equipment 32. The heat exchange equipment 32 may be either a refrigerating mechanism or heating apparatus.

As shown in Figure 1, the side walls 22 is provided with a plurality of access doors 36 having hinges 38 along one vertical edge thereof and a locking hasp 40 located centrally of its other edge. A rain shield 42 in the nature of a ledge may be positioned above each door 36 for rain protection and the like. As shown in Figure 2, the doors 36 are provided on a vertical side wall thereby providing access into the interior of the railroad car 10 from either side for facilitating the loading operation of the railroad car 10. As shown in Figures 3 and 4, a plurality of foraminous screen members 44 are suspended from the top 24 of the railroad car 10 in longitudinally spaced relation thereby forming partial partitions on the interior of the railroad car 10. A pair of guide members 46 are positioned with a portion thereof extending below each of the partitions 44 and the guide members 46 include a vertical section 48 and a horizontal section 50 which forms a continuous path for guiding a slideable partition 52. It will be seen that each of the guide members 46 are formed of a channel-shaped member with the flanges projecting interiorly of the side walls 22. Each slideable partition 52 is constructed of a plurality of panels 54 which are horizontally hinged together by hinges 56 thereby permitting the partition 52 to progress along the guide member 46 from the vertical portion 48 to the horizontal portion 50 as the partition 52 is raised and lowered. The lowermost panel 58 of each of the partitions 52 includes a foraminous screen member 60 for providing ventilation from one compartment to the other. At the lower edge of the panel 58 is secured a hasp member 62 for attachment to an eye member 64 on the floor 20 of the car 10 whereby the slideable partitions 52 may be locked into their vertical closed position by suitable padlocks 66. It will be seen that the double guides 46 and the double slideable partitions 52 which are positioned between adjoining compartments provide extra strength when in their closed position and are easily opened for providing a continuous hollow body portion for the railroad car 10.

In practical operation, the compartments may be lowered to a desired temperature and individual compartments may be opened and unloaded or loaded without disturbing the contents of the other compartments and without anyone removing material from the other compartments. Further, it will be seen that this compartmentation structure may be utilized in highway trucks, ships and any other transportation device. It is also feasible that the particular construction can be utilized in various warehouses concerned with temperature differentials in storing perishable food articles or the like. Obviously, the various elements of this construction may be formed of suitable materials which are readily obtainable thereby assuring the minimum manufacturing cost and consumer cost.

From the foregoing, the construction and operation of the device will be readily understood and further explanation is believed to be unnecessary. However, since numerous modifications and changes will readily occur to those skilled in the art, it is not desired to limit the

invention to the exact construction shown and described, and accordingly, all suitable modifications and equivalents may be resorted to, falling within the scope of the appended claims.

What is claimed as new is as follows:

1. A body for a mobile transportation device comprising a wheeled elongated body having side walls, end walls, a bottom and a top forming a closed hollow body, a plurality of longitudinally spaced access doors in each of said side walls, and a plurality of longitudinally spaced, vertically movable transverse partitions for dividing the interior of said body into a plurality of compartments, said doors providing individual access to each compartment, each side wall being provided with a continuous vertical and horizontal channel shaped guide with the horizontal guide extending from the upper end of the vertical guide, each of said partitions extending between said side walls and positioned in said guides for movement from a vertical closed position to a horizontal open position, each of said sliding partitions including a plurality of pivotally attached sections for permitting said partition to be curved for movement from the vertical guides to the horizontal guides, one of said sections being constructed of foraminous material, and a foraminous partition extending from the top of said body to the upper end of said vertical portion of said guides thereby forming a continuous partition when said movable partition is closed in a vertical position.

2. A body for a mobile transportation device comprising an elongated closed body having a bottom, a top, end walls and side walls, each of said side walls having a plurality of access openings with a closure door

hingedly connected to an edge of each access opening, and a plurality of longitudinally spaced transverse partitions movably mounted between said side walls for dividing the interior of the body into a plurality of compartments, said access openings and door permitting access to individual compartments without disturbing the contents of adjacent compartments, each side wall having a continuous channel shaped guide provided with a horizontal and vertical portion interconnected by a curved portion, each of said movable partitions including a plurality of panels horizontally hinged together by hinge means, the ends of said panels being slidably disposed in said guides whereby the hinge means permits the partitions to move from the vertical portion of the guide to the horizontal portion thereof, the lowermost of said panels being constructed of foraminous material, and means forming a divider extension for each of said partitions, said last named means being rigidly mounted between the side walls adjacent the upper end thereof.
